TRACK STRUCTURE

John Norman Tyler, Woodbury Heights, N. J.

Application June 2, 1938, Serial No. 211,444

1 Claim. (Cl. 238—10)

This invention relates to a track structure for a toy railway train, and it is an object of the invention to provide a road bed particularly designed and adapted for use in connection with that class of toy railways wherein both rails of the trackway serve as conductors for the electrical energy.

The invention also has for an object to provide a structure of this kind including a road bed of a material non-conductive of electricity together with means whereby the track may be readily and effectively held to such road bed.

An additional object of the invention is to provide a structure of this kind with a road bed of a material non-conductive of electricity and which road bed is so formed and constructed to simulate cross ties.

The invention also contemplates for an object to provide a road bed which provides for quiet operation and which also results in the production of a road bed in simulation of a regular track-way.

The invention consists in the details of construction and in the combination and arrangement of the several parts of my improved track structure whereby certain important advantages are attained and the device rendered simpler, less expensive and otherwise more convenient and advantageous for use, as will be hereinafter more fully set forth.

The novel features of my invention will herein-after be definitely claimed.

In order that my invention may be the better understood, I will now proceed to describe the same with reference to the accompanying drawing, wherein

Figure 1 is a view in top plan of a track structure constructed in accordance with an embodiment of my invention;

Figure 2 is a view similar to Figure 1 illustrating another embodiment of the invention;

Figure 3 is a fragmentary view in top plan with portions broken away of a structure constructed in accordance with a still further embodiment of the invention;

Figure 4 is enlarged transverse sectional view taken substantially on the line 4—4 of Figure 1;

Figure 5 is an enlarged transverse sectional view taken substantially on the line 5—5 of Figure 2;

Figure 6 is a fragmentary view in side elevation of the meeting end portions of rails illustrating means for connecting the same;

Figure 7 is a sectional view taken substantially on the line 7—7 of Figure 6;

Figure 8 is a fragmentary view in top plan of the road bed strip as comprised in Figure 1.

In the embodiment of the invention as illustrated in Figures 1, 4 and 8 the assembly is particularly adapted for use in connection with a straight trackway. The rails 1 are solid and rest directly upon the elongated strips 2 of a fibre material non-conductive of electricity and which rails 1 are held to the strips 2 by the metallic clips 3. The strips 2 at spaced points therealong are connected by the transversely disposed cross strips 4 which serve to maintain the strips 2 in desired spaced relation and at the same time give a close simulation of cross ties. These cross members or strips 4 are integral with the strips 2. The strips 2 in alignment with the cross strips 4 are also provided with the outstanding tie extensions 5 integral therewith to further increase the simulation of ties.

As illustrated in Figures 6 and 7 the meeting ends of the rails are effectively connected by an elongated metallic clip 6 which engage the flanges of the rails. This clip 6 can be readily slid along one rail 1 to disconnect adjacent rails and vice versa.

In the embodiment of the invention as illustrated in Figure 2, the strips 1, the cross strips 4 and extensions 5 are placed upon a felt strip 7 which further enhances the simulation of a road bed but particularly makes for quiet operation as the toy electric train travels along the tracks. The felt strip 7 after being laid down in desired position has disposed thereover a lamination of suitable adhesive to assure the proper maintenance of the strips 2 and their associated elements in place upon the strip 7.

While this adhesive is still tacky sand or the like is sprinkled over the entire remaining exposed portion of the strip and after the adhesive has dried the surplus sand or the like is brushed away leaving an imitation stone road bed with ties and rails in place.

In the embodiment of the invention as illustrated in Figure 3, a felt strip 8 is employed and is finished in substantially the same manner as hereinbefore stated with respect to the strip 7. The tracks 9, however, are curved and in order that the transverse or tie strips 10 associated with the straight strips 11 may be properly adjusted to compensate for the curvature of the tracks, the straight strips 11 between certain of the adjacent cross or tie strips 10 are cut out, as at 12, it being understood of course that the strips 11 possess the required initial flexibility.

In connection with switches and cross overs

the suitably bent rails are held to the insulated base and the general assembly otherwise is substantially the same as has hereinbefore been set forth in connection with the rail sections.

6 From the foregoing description it is thought to be obvious that a track structure constructed in accordance with my invention is particularly well adapted for use by reason of the convenience and facility with which it may be assembled and 10 operated, and it will also be obvious that my invention is susceptible of some change and modification without departing from the principles and spirit thereof and for this reason I do not wish to be understood as limiting myself to the 15 precise arrangement and formation of the several parts herein shown in carrying out my invention in practice except as hereinafter claimed.

I claim:

A roadbed for toy trains wherein the rails constitute electrical conductors, strips of a flexible material non-conductive of electricity on which the rails rest, means for securing the rails to said strips, and transversely disposed tie strips integrally formed with the first named strips and disposed transversely thereof, said last named strips being also of a material non-conductive of electricity, one of said first named strips at one or more points therealong being cut away entirely thereacross between adjacent transverse strips whereby said one of the first named strips is divided into sections to allow lateral flexing of the roadbed to compensate for curvature of the rails. 5 10 15

JOHN NORMAN TYLER.
